UNITED STATES PATENT OFFICE.

MILES SHAFFER, OF LAKE LINDEN, MICHIGAN.

LOCATING-BUOY.

1,295,805.

Specification of Letters Patent. Patented Feb. 25, 1919.

Application filed July 18, 1917. Serial No. 181,325.

To all whom it may concern:

Be it known that I, MILES SHAFFER, a native citizen of the United States, residing at Lake Linden, in the county of Houghton and 5 State of Michigan, have invented new and useful Improvements in Locating-Buoys, of which the following is a specification.

This invention relates to an apparatus for locating sunken ships and comprehends the 10 provision of a buoy which will be automatically floated from the ship when it sinks, said buoy being secured by a flexible connection to an automatic reel fixed to the ship.

Another and more specific object of the 15 invention is to provide an apparatus of this nature, a reel from which a flexible connection may be unwound if pulled suddenly or rapidly, but which will automatically lock when brought to rest by the settling of the 20 vessel to which it is attached on the bottom.

The invention has for a further object the provision of a novelly constructed buoy mounted in a container and carrying a bell.

With these and other objects in view as 25 will become more apparent as the description proceeds, the invention consists in certain novel features of construction, combination and arrangement of parts as will be herein-after fully described, illustrated and claimed.

30 In the drawings,

Figure 1 is a view showing the buoy floated from a sunken vessel.

Fig. 2 is a vertical sectional view through the apparatus assembled and attached to a 35 ship, taken on a plane passing at right angles to the axis of the reel.

Fig. 3 is a central longitudinal sectional view, partly in elevation through the reel.

Fig. 4 is a perspective view showing the 40 cam end of the reel.

Referring in detail to the drawings by numerals, 1 designates a ship to any suitable place on which may be secured my locating apparatus which comprises in general 45 a buoy 2, container 3 and reel 4.

The buoy is preferably made with an inverted hollow conical body 5 weighted at its lower end as at 6 and closed at its upper end by a head 7, the inclined side wall of 50 which projects downwardly beyond the upper edge of the body 5 to overhang the same. A bell 8 is mounted in a suitable frame 9 on top of the buoy.

In normally assembled position, the buoy 55 rests in the tubular container 3 which may be secured to a vessel by suitable fasteners

passing through the base flange 10. The upper end of the container is slightly flared as at 11 so as not to cause excessive wear to a flexible connection to be hereinafter 60 designated and the side wall 12 of the buoy head 7 overlies the upper edge of the container so as to shed water therefrom. Openings 13 may be formed in the container so as to break a vacuum and allow the buoy to 65 be easily floated when the vessel sinks.

The buoy is connected by a wire 14 or other flexible connection to the drum 15 of the reel 4. The drum has the heads 16 and is fixed to a shaft 17 journaled in bearings 70 18 in a frame 19 having side members 20. The frame is secured to the vessel within the container and holds the reel in such position that the line or flexible connection 14 may be freely fed therefrom when the 75 vessel sinks.

The reel is equipped with an automatic stop device which includes a cam rim 21 having a notch 22 into which a locking bolt 23 may be snapped to stop the rotation of the 80 reel. The locking bolt slides longitudinally through a housing 24 in which is an expansive helical spring 25 which engages the enlargement 26 on the bolt to urge the latter toward the reel. The housing is secured at 85 right angles to the outer side of one of the side members 20 which latter is apertured to permit the passage of the bolt 23 therethrough. When the reel is revolved rapidly the bolt which is moved outwardly by the 90 cam rim will not be moved inwardly fast enough by its spring 25 to snap into the notch 22 but when the rotation of the reel stops or slows down sufficiently the bolt will 95 become operative.

A partition or division plate 27 is fixed horizontally within the container above the reel and is slotted as at 28 to afford passage for the connection 14. In order that the reel may be initially started, to revolve very rapidly so as to render the locking feature inactive, I coil about 100 feet of the line 14 on to the partition so that the reel will not be jerked until the vessel has sunk to this depth at which time it is dropped very rapidly and, therefore, will start the reel at an initially high speed so as to cause the notch in the cam rim to fly past the locking bolt. When the vessel settles to the bottom, the locking bolt will operate to hold the reel 100 stationary so as to not release further length of line and, therefore, it is evident that the 105 110

buoy will always flow approximately over the vessel and designate its location. This automatic locking feature is of great importance since it prevents the buoy drifting a great distance away from the vessel in which event its line would be apt to become entangled in passing ships or might drift against nearby land or rocks and therefore have its purpose defeated.

10 From the foregoing description taken in connection with the accompanying drawings, it will be evident that I have provided a very simple and practical apparatus for locating sunken vessels which apparatus is especially adapted for use on ships sailing in land waters whose depth is not prohibitive.

What I claim is:—

1. A buoy having a hollow inverted conical body weighted at its lower end, and a head closing said body having an inclined side wall overhanging the body.

2. In combination with a tubular con-

tainer adapted to be secured at one end to a vessel, a buoy having a body extending into the upper open end thereof and closely engaging the same, and a head for said buoy having an inclined wall overhanging the upper edge of the container, said container being formed with openings.

3. In an apparatus of the character described, a reel, a buoy, a line connecting said buoy to the reel, and means for locking the reel, said means being compressed when the reel is rotated at high speed.

4. In an apparatus of the character described, a buoy, a container therefor, a reel, a line connecting said reel to the buoy, a partition in said container to which the line passes and on which a length of the line may be coiled and locking means for the reel, said means being compressed when the reel is revolved at high speed.

In testimony whereof I affix my signature.

MILES SHAFFER.
